UNITED STATES PATENT OFFICE.

EDMUND HUGH PRYCE, OF NEW YORK, N. Y., ASSIGNEE, BY DIRECT AND MESNE ASSIGNMENTS, TO GENERAL HEATING CORPORATION OF AMERICA, A CORPORATION OF NEW YORK.

LIQUID-FUEL HEATER.

1,359,917.

Specification of Letters Patent. Patented Nov. 23, 1920.

Application filed March 4, 1919. Serial No. 280,635.

To all whom it may concern:

Be it known that I, EDMUND HUGH PRYCE, a subject of the King of Great Britain, residing at the city of New York, in the borough of Manhattan and State of New York, have invented certain new and useful Improvements in Liquid-Fuel Heaters, of which the following is a full, clear, and exact description.

10 My invention relates to heaters and particularly to heaters designed to burn hydro-carbon oil as the fuel.

15 Objects of the invention are economy in fuel consumption, efficiency in heat generation and inexpensiveness, simplicity and compactness of construction. Another object is to prevent escape of the fuel when for any reason the apparatus becomes inoperative, as for example, when the flame has been accidentally extinguished. Another 20 object is facility in assembling the structure in a furnace. Still other objects and advantages of my invention will appear from the following description.

25 In accordance with my invention, the oil is first heated to a vaporizing temperature and in this active condition the vapor is brought into intimate contact with superheated steam, and the gas mixture so formed is superheated and immediately burned. Preferably a stream of the vapor is formed and mingled with a stream of the steam and the mixture is then allowed to suddenly expand. Under these conditions practically 35 all of the carbon content of the fuel combines with the free oxygen of the decomposed steam to form carbon monoxide, and a gas is formed which is completely combustible.

30 My invention comprehends, as an apparatus for carrying out this process, a base burner and a superstructure in the region of the heat of the burner, in which there is a vaporizing compartment for the oil, steam generating and superheating compartments, a 40 mixing chamber and a superheating compartment for the gas which communicates with the mixing chamber and from which the gas is led to the base. The vaporizing compartment preferably comprises a plurality of tubes connected to cause the oil to 45 pass back and forth in the heated area until it vaporizes, whereupon the vapor passes into the mixing chamber through a restricted orifice. Closely adjacent the vapor orifice is

another restricted orifice through which the 55 superheated steam enters, the orifices being directed to cause the two streams to intermingle. The gas superheating compartment preferably comprises a plurality of relatively small tubes running horizontally 60 through the region of the heat, for the purpose of dividing the gas to heat it more effectively.

To automatically cut off the fuel supply should the flame become accidentally extinguished, the fuel inlet pipe is provided with a float-controlled valve, and the tube conducting the vapor to the mixing chamber has a portion extending up to the level of the float controlled valve. In the event that 70 the flame becomes extinguished, the fuel is no longer vaporized, and the liquid fuel will rise in the system to the height in the vapor conducting tube, which is the height of the float-controlled valve, and the valve will be 75 thereby closed and the fuel supply cut off.

To facilitate the insertion of the device in the relatively small door of a furnace, it is preferably made in a plurality of easily 80 separated units which may be readily assembled in the furnace and which are individually small enough to pass through the furnace door. A convenient construction is one in three units, one unit comprising the base, another unit comprising the steam 85 generating and drying chambers, the oil vaporizing compartment, the mixing chamber and the gas superheating compartments, and the third unit comprising the steam superstructure and the upward extension of 90 the vapor passage constituting the safety feature.

95 My invention also comprehends other features of construction and details and arrangements of parts as will hereinafter more fully appear.

I shall now describe the illustrated embodiment of my invention and shall thereafter point out my invention in claims.

Figure 1 is a front end elevation of a 100 heating apparatus embodying my invention,

Fig. 2 is a longitudinal sectional elevation of the same on the broken line 2—2 of Fig. 1;

Fig. 3 is a rear end elevation of the same without the base;

Fig. 4 is a longitudinal central sectional elevation of the front end portion of the parts shown in Fig. 3;

Fig. 5 is a similar view of the rear end portion of the same;

Fig. 6 is a vertical transverse sectional elevation on the line 6—6 of Fig. 4;

5 Fig. 7 is a diagrammatic representation of the system, with the heating apparatus installed in a furnace and shown in sectional elevation as viewed from the front;

10 Fig. 8 is a detail, in sectional elevation, of the fuel cut-off valve and float control therefor.

In the illustrated apparatus the base 1 is an oblong rectangular member open at the bottom and provided on its top with suitable combustion burners and on its ends with upright posts 2 and 3, the latter post being hollow and communicating with a longitudinal gas tube 4, along the top of which are a plurality of gas outlets 4*. The posts 2 and 3 support the superstructure, as will presently be described.

In the form shown, the oil preheating tubes 5 and 6 and the oil vaporizing tube 7 and the gas superheating tubes 8, 9 and 10 are made in a single casting. The oil preheating and vaporizing tubes 5, 6 and 7 are somewhat longer than the tubes 8, 9 and 10 and extend beyond the latter at both ends, and cylindrical cup-shaped members 11 and 12 unite the vaporizing tube 7 with the tubes 8, 9 and 10 at the front and rear ends respectively, the cylindrical walls of which extend flush with the respective ends of the oil tubes 5, 6 and 7 and form a mixing chamber 13 (Fig. 4) and a collecting chamber 14 (Fig. 5) respectively. The three tubes 8, 9 and 10 open into both chambers. The oil preheating tubes 5 and 6 are joined at their front ends by a passage 15 formed in the casting, and the tube 6 and the vaporizing tube 7 are joined at their rear ends by a passage 16 formed in the casting. End plates 17 and 18, secured by bolts to the casting, form the outer walls for the chambers 13 and 14, and for the passages 15 and 16, and close the ends of the oil tubes 5, 6 and 7. Both end plates have integral depending projections 19 and 20, respectively, which are recessed to fit upon reduced upper ends of the posts 2 and 3. The projection 20 is hollow, having a passage 21 which communicates with the chamber 14 and forms a continuation of the passage in the hollow post 3.

55 Arranged on opposite sides of the casting are two shells 22 and 23 which are bolted to the end plates 17 and 18 and serve as steam generating and drying chambers, the former being a steam generating boiler and drier, and the latter a steam drier. These shells are provided with longitudinal partitions 22* and 23*, respectively, which divide them into compartments or tubes, and the upper tube of the steam generating boiler 22 communicates with the lower tube of the

steam drying chamber 23 through a conduit 24 cast integral with the front plate 17. The rear end of the upper tube of the steam drying chamber 23 communicates through a conduit 25 with the longitudinal steam 70 superheating tube 26 which extends along the top of the device. The conduit 25 is formed in two parts, one of which is cast integral with the rear plate 18 and the other of which is carried by the steam 75 superheating tube 26, the two parts being bolted together, as indicated in Fig. 3. The top of the mixing chamber 13 is provided with a circular opening, as appears in Fig. 4, and over this is secured an upright tubular projection 27 closed at its top and having an annular recess 28 surrounding the central bore and forming an annular orifice 29, the walls of which converge downwardly as shown in Fig. 4. The steam superheating tube 26 communicates with the annular recess 28.

A vapor conducting tube 30 screws into the top of the oil vaporizing tube 7 at its forward end and extends vertically through 90 the mixing chamber 13 into the tubular projection 27 and terminates near the top of the tubular projection.

To initiate the operation of the heater, the device is preliminarily heated by igniting an 95 oil-saturated wick in the usual way. This wick is contained in a chamber 31 on top of the base 1. Oil from the tank 32 is admitted to the wick chamber 31 through a branch pipe 33 controlled by the cock 33*. 100 When the vaporizing superstructure has become sufficiently heated, oil is admitted through the pipe 34 to the rear end of the tube 5, which passes through the tube 5, the passage 15 and the tube 6, and thence 105 through the passage 16 into the tube 7. The oil is preheated during its passage through the pipes 5 and 6, and is converted into vapor in the tube 7, which is of somewhat larger diameter than the preheating 110 tubes. From the tube 7 the vapor rises through the tube 30 to the top of the tubular extension 27, and thence passes down outside the tube 30 through the restricted annular orifice 35 into the mixing chamber 13 and 115 through the superheating tubes 8, 9 and 10 to the collecting chamber 14 whence it is conducted through the passage 21 to the gas tube 4 in the base, and escapes through the outlets 4*, at which point it mingles with 120 pre-heated air passing up through the base, and this carbureted mixture is ignited at the top of the burners 36.

When the superstructure has become sufficiently hot, water is admitted from the tank 125 37 through a pipe 38 to the rear end of the lower tube or compartment of the boiler 22. Here it is immediately flashed into steam which passes through the three tubes of the boiler 22 and thence through the passage 130

24 to the bottom of the steam drying chamber 23 and thence through the three tubes of this chamber and the passage 25 to the steam superheating tube 26, and thence 5 through the orifice 29 into the mixing chamber, being directed by the inclination of the walls of the orifice 29 into the stream of vapor entering through the orifice 35. The mixture, after being thus intimately combined, expands in the mixing chamber 13 during which the chemical reactions occur, and the gas then passes through the superheating tubes 8, 9 and 10 to the chamber 14 and thence to the base where it is burned. 10 In the oil pipe 34, there is provided a float-controlled needle valve 39, shown in detail in Fig. 8. The valve member 40 is controlled by the float 41 in the chamber 42 and when this float rises it depresses the 15 inner ends of pivoted levers 43 which engage between collars on the valve stem 40, and thereby depress the valve stem and close the valve. This operation will take place only when liquid oil sufficiently fills the chamber 20 42. As long as the oil is consumed at the heater, the liquid oil merely flows upward through the needle valve and thence down through the nipple 44 into the continuation of the pipe 34. Should 25 anything occur, however, by reason of which the oil is not consumed at the heater, as when the flame at the burners is extinguished, then the liquid oil flows into the system and rises through the tube 30 to a height in the tubular projection 27 which is at least as high as the float 41. In this event, the oil rises in the chamber 42 until the float operates to close the needle valve. 30 As shown in Fig. 7, the heater is set on the grate bars of any usual coal furnace. In order to cause the air to pass through the base, the portion of the grate outside the base is preferably covered with a suitable composition, such as a sand filler 45, resting 35 upon a metal footing or plate 46. To install the heater in the furnace, the base is first put in, then the intermediate unit is set upon the posts 2 and 3, and finally the top unit is secured in place. The latter operation involves 40 screwing the tube 30 into the top wall of the tube 7, putting the tubular projection 27 over the tube 30 and screwing it to the top of the wall of the mixing chamber, as shown in Fig. 7, and bolting together 45 the two portions of the conduit 25.

The combustion burners 36, which are shown in detail in Fig. 2, have proven to be highly efficient. They consist of a plurality of concentric straight tubes, and I have found three to be very satisfactory for the purpose. The tubes are secured together in any suitable way in spaced relation, and are preferably of substantially uniform length, but arranged progressively higher from the 50 inner to the outermost.

It is obvious that various modifications may be made in the construction shown in the drawings and above particularly described within the principle and scope of my invention.

70

I claim:

1. In an oil burning heater, in combination with a base including a combustion burner, a superposed vaporizing device comprising an oil preheating and vaporizing compartment, a steam generating boiler and a water inlet therefor, a mixing chamber communicating with the boiler and oil vaporizing compartment by adjacently disposed inlets, and a conduit providing communication between the mixing chamber and the base and including therein a mixture superheating compartment.

2. In an oil burning heater, in combination with a base including a combustion burner, a superposed vaporizing device comprising an oil preheating and vaporizing compartment, a steam generating boiler and a water inlet therefor, a steam superheating passage communicating with the boiler, a mixing chamber communicating with the steam superheating passage and oil vaporizing compartment by adjacently disposed restricted inlets, and a conduit providing communication between the mixing chamber and the base and including therein a plurality of mixture superheating compartments.

3. In an oil burning heater, in combination with a base including a combustion burner, a superposed vaporizing device comprising an oil preheating and vaporizing compartment, a steam generating boiler and a water inlet therefor, a steam superheating passage communicating with the boiler, a mixing chamber for the vapor and steam having two concentric inlet passages, one communicating with the oil vaporizing compartment and the other with the steam superheating passage, and a conduit providing communication between the mixing chamber and the base and including therein a mixture superheating compartment.

4. In an oil burning heater, in combination with a base including a combustion burner, a superposed vaporizing device comprising an oil preheating and vaporizing compartment, a steam generating boiler and a water inlet therefor, a steam superheating passage communicating with the boiler, a mixing chamber communicating with the steam superheating passage and oil vaporizing compartment by adjacently disposed restricted inlets, a gas superheating compartment communicating with the mixing chamber, and a conduit providing communication between the gas superheating compartment and the base.

5. In an oil burning heater, in combination, a burner, a compartment for vaporiz- 130

- ing the oil, another compartment for generating steam, means for bringing the vapor and steam into intimate mixture comprising a mixing chamber and adjacently disposed restricted inlets communicating respectively with the vaporizing and steam generating compartments, and a connection between the mixing chamber and burner having intermediate thereof a mixture 5 preheating compartment.
6. In an oil burning heater, in combination with a base including a combustion burner, a superposed vaporizing device comprising a horizontally disposed oil receiving and preheating tube, a horizontally disposed oil vaporizing tube communicating with the oil preheating tube, a steam generating boiler, a mixing chamber having restricted concentric inlets communicating respectively with the oil vaporizing tube and the boiler, and a plurality of horizontally disposed gas superheating tubes communicating with the mixing chamber and with the base.
7. In an oil burning heater, in combination with a base including a combustion burner, a superposed vaporizing device comprising an oil vaporizing compartment, a steam generating boiler, a steam drying compartment communicating with the boiler, a steam superheating tube communicating with the drying compartment, and a mixing chamber having restricted concentric inlets communicating respectively with the oil vaporizing compartment and the steam superheating tube.
8. In an oil burning heater, in combination with a base including a combustion burner, a superposed vaporizing device comprising an oil vaporizing compartment, a steam generating boiler, a steam drying compartment communicating with the boiler, a steam superheating tube communicating with the drying compartment, a mixing chamber having restricted concentric inlets communicating respectively with the oil vaporizing compartment and the steam superheating tube, and a plurality of gas superheating tubes communicating with the mixing chamber and the base.
9. In an oil burning heater, in combination, a compartment for vaporizing the oil, a steam generating boiler, a mixing chamber for the steam and vapor having at one side a tubular extension closed at its outer end and an annular orifice surrounding the tubular opening, a vapor conducting tube leading from the vaporizing compartment through the mixing chamber and extending into the tubular opening leaving a restricted inlet for the vapor surrounding the tube, and a conduit connecting the boiler with the first mentioned annular orifice.
10. In an oil burning heater, in combination, a compartment for vaporizing the oil,
- a steam generating boiler, a mixing chamber for the steam and vapor having at one side a tubular extension closed at its outer end and an annular orifice surrounding the tubular opening, a vapor conducting tube leading from the vaporizing compartment through the mixing chamber and extending into the tubular opening leaving a restricted inlet for the vapor surrounding the tube, a conduit connecting the boiler with the first mentioned annular orifice, and a plurality of gas superheating tubes leading from the mixing chamber.
11. In an oil burning heater, in combination, a combustion burner, a compartment for vaporizing the oil, an oil inlet tube leading thereto, means including a float controlled valve for cutting off the supply of fuel when the vaporizing compartment fills with oil, but permitting the oil to flow freely into said compartment when the compartment is not entirely filled.
12. In an oil burning heater, in combination, a base including a combustion burner, a compartment for vaporizing the oil, an oil inlet tube leading thereto, a float-controlled valve in the inlet tube, a steam generating boiler, a mixing chamber for the steam and vapor disposed over the vaporizing compartment and having on its top a tubular extension extending at least to the level of the float controlled valve and closed at its top end, a vertical vapor conducting tube leading from the vaporizing compartment through the mixing chamber and extending into the tubular opening to the level of the float controlled valve, a conduit leading from the boiler into the mixing chamber, and a communicating conduit between the mixing chamber and the base.
13. In an oil burning heater, in combination, a base including a combustion burner, a compartment for vaporizing the oil, an oil inlet tube leading thereto, a float-controlled valve in the inlet tube, a steam generating boiler, a mixing chamber for the steam and vapor disposed over the vaporizing compartment and having on its top a tubular extension extending at least to the level of the float controlled valve and closed at its top end, a vertical vapor conducting tube leading from the vaporizing compartment through the mixing chamber and extending into the tubular opening to the level of the float controlled valve, a conduit leading from the boiler into the mixing chamber and having its orifice adjacent the tubular opening, and a gas superheating compartment communicating with the mixing chamber and the base.
14. In an oil burning heater, in combination with a base including a combustion burner, a superposed vaporizing device comprising a casting including a horizontal oil preheating tube, a horizontal oil vaporizing

- tube communicating with the oil preheating tube, a plurality of horizontal gas superheating tubes, and a casing at each end forming a mixing chamber at one end and a collecting chamber at the other end of the superheating tubes; a conduit providing communication between the vaporizing tube and mixing chamber, two end plates arranged to close the outer ends of the oil preheating and vaporizing tubes and of the mixing and collecting chambers, and a conduit leading from the collecting chamber to the base.
15. In an oil burning heater, in combination with a base including a combustion burner, a superposed vaporizing device comprising a casting including a horizontal oil preheating tube, a horizontal oil vaporizing tube communicating with the oil preheating tube, a plurality of horizontal gas superheating tubes, and a casing at each end forming a mixing chamber at one end and a collecting chamber at the other end of the superheating tubes; a conduit providing communication between the vaporizing tube and mixing chamber, two end plates arranged to close the outer ends of the oil preheating and vaporizing tubes and of the mixing and collecting chambers, a conduit leading from the collecting chamber to the base, two communicating tubular boilers arranged on opposite sides of the casting and supported by the end plates, a water inlet for one boiler, and a conduit connecting the other boiler with the mixing chamber.
16. In an oil burning heater, in combination with a base including a combustion burner, a superposed vaporizing device comprising a casting including a horizontal oil preheating tube, a horizontal oil vaporizing tube communicating with the oil preheating tube, a plurality of horizontal gas superheating tubes, and a casing at each end forming a mixing chamber at one end and a collecting chamber at the other end of the superheating tubes; a conduit providing communication between the vaporizing tube and mixing chamber, two end plates arranged to close the outer ends of the oil preheating and vaporizing tubes and of the mixing and collecting chambers, a conduit leading from the collecting chamber to the base, two communicating tubular boilers arranged on opposite sides of the casting and supported by the end plates, a water inlet for one boiler, and a steam superheating tube communicating at one end with the other boiler and at its other end with the mixing chamber.
17. In an oil burning heater, in combination with a base including a combustion burner, a superposed vaporizing device comprising a casting including a horizontal oil preheating tube, a horizontal oil vaporizing tube communicating with the oil preheating tube, a plurality of horizontal gas superheating tubes, and a casing at each end forming a mixing chamber at one end and a collecting chamber at the other end of the superheating tubes; two end plates arranged to close the outer ends of the oil preheating and vaporizing tubes and of the mixing and collecting chambers, a conduit leading from the collecting chamber to the base, a vertical tubular extension on the mixing chamber closed at its top, and a vertical vapor conducting tube leading from the vaporizing chamber through the mixing chamber and within the tubular opening of the tubular extension.
18. In an oil burning heater, in combination with a base including a combustion burner, a superposed vaporizing device comprising a casting including a horizontal oil preheating tube, a horizontal oil vaporizing tube communicating with the oil preheating tube, a plurality of horizontal gas superheating tubes, and a casing at each end forming a mixing chamber at one end and a collecting chamber at the other end of the superheating tubes; two end plates arranged to close the outer ends of the oil preheating and vaporizing tubes and of the mixing and collecting chambers, a conduit leading from the collecting chamber to the base, a vertical tubular extension on the mixing chamber closed at its top, a vertical vapor conducting tube leading from the vaporizing chamber through the mixing chamber and within the tubular opening of the tubular extension, two communicating tubular boilers arranged on opposite sides of the casting and supported by the end plates, a water inlet for one boiler, and a steam superheating tube communicating at one end with the other boiler and at its other end with the mixing chamber.
19. A multi-unit oil burning heater comprising as one unit a base including a gas compartment and combustion burners and two upright posts, one of which is hollow and communicates with the gas compartment, and comprising as another unit a superposed vaporizing device including an oil vaporizing tube, a gas superheating tube, a steam generating boiler, a mixing chamber communicating with both tubes and the boiler, and two end plates provided with a depending post adapted to fit upon the upper ends of the posts on the base and the post at the one end being hollow and communicating with the gas superheating tube.
20. A multi-unit oil burning heater comprising as one unit a base including a gas compartment and combustion burners and two upright posts, one of which is hollow and communicates with the gas compartment, and comprising as another unit a superposed vaporizing device including an oil vaporizing tube, a gas superheating tube,

a steam generating boiler, a mixing chamber communicating with both tubes, two end plates provided with a depending post adapted to fit upon the upper ends of the 5 posts on the base and the post at the one end being hollow and communicating with the gas superheating tube, and comprising as a third unit a steam superheating tube communicating with the mixing chamber, a two- 10 part separable conduit connecting the boiler with the steam superheating tube, an upright tubular extension on the mixing chamber, and a vapor conducting tube removably secured in the oil vaporizing tube and extending upward into the tubular extension. 15

21. The process of generating gas consisting of heating a hydro-carbon oil at one place until it vaporizes, generating and superheating steam at another place, and at 20 a third place bringing a thin stream of the vapor and superheated steam together and allowing them to expand and then superheating the gas so formed.

22. A combustion burner for gas comprising, in combination with a gas conductor having an outlet therein, a plurality of spaced concentric cylindrical tubes arranged directly above the gas outlet and extending 25

progressively higher from the inner to the outermost. 30

23. A combustion burner for gas comprising, in combination with a gas conductor having an outlet therein, a plurality of spaced concentric cylindrical tubes arranged directly above the gas outlet, the tubes being of substantially the same length and arranged progressively higher from the inner to the outermost. 35

24. In an oil burning heater, in combination, a combustion burner, an oil supply conduit, a float controlled valve connected in said supply conduit, an oil vaporizer arranged in said conduit beyond and below the level of the float controlled valve, said conduit beyond the vaporizer rising to a 40 height at least equal to the height of the float valve, and then passing to the burner, whereby when the vaporizer is effective the float controlled valve is always open and when the vaporizer is ineffective and the level of the liquid rises above the vaporizer, the float controlled valve is automatically closed. 45

In witness whereof I subscribe my signature.

EDMUND HUGH PRYCE
